UNITED STATES PATENT OFFICE.

WILLIAM R. STONE AND ALBERT W. PRATT, OF SALEM, MASSACHUSETTS.

MACHINE FOR TREATING HIDES.

SPECIFICATION forming part of Letters Patent No. 318,820, dated May 26, 1885.

Application filed January 5, 1885. (No model.)

To all whom it may concern:

Be it known that we, WILLIAM R. STONE and ALBERT W. PRATT, of Salem, county of Essex, State of Massachusetts, have invented 5 an Improvement in Machines for Treating Hides, of which the following description, in connection with the accompanying drawings, is a specification, like letters on the drawings representing like parts.

10 This invention has for its object the production of a machine adapted to unhair hides; and with a slight change of parts the same machine is adapted for cleaning the hide from the drench-liquor. In machines for unhairing and handling wet hides the operators, in placing the hides in the machine, are frequently seriously injured; but in the machine herein to be described the construction is such that there is no serious danger of accident to the 15 operator. In our improved machine the hide to be unhaired, and in its usual state for such operation, has one end passed under the unhauling-blade, attached to a pivoted beam or cross-bar, mounted, preferably, in adjustable 20 bearings, and is led over a spreading or stretching table, and its end is then placed under a flexible loop attached to the hide-drawing roller, having an attached friction-clutch mechanism by which to rotate the said roller, and 25 the roller is started, with the hide upon it, such action causing the balance of the hide to be drawn between the unhauling-blade and the stretching bed or table. The hide is then removed from the roller and is turned end for 30 end and again drawn through the machine, thus completing the unhauling operation. In all other machines the end of the hide to be drawn through the machine between the unhauling-blade and the table is secured to the 35 end and again drawn through the machine, thus completing the unhauling operation. In all other machines the end of the hide to be drawn through the machine between the unhauling-blade and the table is secured to the 40 pulling-roller by a clamp, under which the end of the hide has to be secured, with considerable trouble and waste of time, and the operator is liable to be injured if the machine is prematurely started. In this our invention 45 we have provided the drawing-roller with a flexible loop or chain under which the end of the hide may be quickly drawn as the roll is started, the operator holding the hide partially bent above the flexible loop until in the 50 rotation of the roller the loop commences to draw upon the hide, and thereafter the fric-

tion of the loop on the hide on one side and of the roller on the other side draws the hide with the roller. By means of the loop the hide may be more quickly engaged with and 55 so as to be moved by the roller than were a clamp employed, and the action of the loop on the hide so holds it, as we consider, more satisfactorily than were a metal rod or clamp employed. 60

Figure 1 is a front view of a hide-treating machine embodying our invention; Fig. 2, a top or plan view; Fig. 3, a right-hand end view; and Fig. 4, a section in the line *xx*, Fig. 1. 65

The frame-work *A* has suitable bearings for the reception of the roller *B*, provided with the flexible loop *a*, a rope, or string, cord, or a chain. The roller *B* has mounted loosely on it a toothed wheel, *b*, having a projecting 70 flange, *b'*, the interior of which is engaged by the friction-faces of blocks *b*², connected by links *b*³ with a collar, *b*⁴, splined on the shaft of roller *B*, the said collar being grooved to be embraced by a forked lever, *c*, joined by a 75 suitable link, *c'*, with a treadle, *c*², whereby the operator by his foot may effect the engagement or disengagement of the clutch parts *b*² and *b*² at will, according as he desires to rotate or to stop the rotation of the roller *B*. The blocks 80 *b*² slide in slots of an arm, *b*⁵, secured to the shaft of the roller *B*. The loose gear is driven by the pinion *d* on the driver-shaft *d'*, having a belt-receiving pulley, *d*². The stretching bed or table *C*, preferably of metal, has a series of teeth, *C*², which diverge each way from the center of the bed in the direction of the movement of the hide over it, as best shown in Figs. 2 and 1, to thus stretch or spread out the hide, the said bed also being inclined upwardly in the direction of its width between the roller and the blade, to be described as indicated in Fig. 4. The frame-work at the rear side of the mechanism has grooved uprights *e*, in which are placed plumber-boxes 90 *e*, the said boxes being supported on springs *e*², and being acted upon at their upper side by adjusting-screws *e*², whereby the said boxes may be adjusted vertically. The plumber-boxes *e* receive the end journals of a beam or 100 rocker, *f*, having a handle, *f*², by which to turn it in the direction of the arrow 2, Fig.

4, to permit the hide *h* (shown in dotted lines) to be introduced under the unhairing-blade *g*, composed of steel, and held adjustably by the screws *g'*, a cap, *g''*, or binder, being introduced between the heads of the said screws and the beam. The beam has projecting arms *f'*, which come against adjusting devices *m*, (shown as screws,) held in uprights *m'* of the frame, the adjustment of the said 10 screws determining the angle of presentation of the edge of the blade *g* to the hide. The end of the hide caught under the flexible rope or cord *a* is firmly held, and as the roller is rotated the hide is moved on the roller and 15 drawn through the machine.

The machine shown is provided with a strong strip of vulcanized india-rubber—such as belting—and shown at *p*.

In one of the treatments of hides the liquor 20 with which the hide is drenched has to be stripped or squeezed out. To do this, loosen the screws *g'* and lift the blade *g* until the edge of the india-rubber strip is as low or lower than the blade *g*, and thereafter the said india-rubber strip will act as the surface against 25 which the surface of the hide will be drawn as it is pulled over the table *C* by the roller.

We do not claim a metal rod or clamp attached to a roller and serving to hold one end 30 of a hide, as that is old.

We claim—

1. In a hide-treating machine, a bed or table combined with a drawing-roller provided with a flexible loop with which to engage the end or edge of the hide to draw it across the bed 35 or table, substantially as described.

2. The bed or table provided with the diagonally-placed teeth to shield the hide, and the roller having the attached flexible loop *a*, combined with the beam and its attached 40 metal blade *g*, to operate substantially as described.

3. The bed or table and the drawing-roller provided with the flexible loop *a*, combined with the beam mounted in adjustable plumber- 45 boxes, and with the blade *g*, attached to the said beam, substantially as described.

4. The bed or table and the drawing-roller having the flexible loop *a*, combined with the beam provided with a strip of india-rubber to 50 work out the drench-liquor, substantially as described.

In testimony whereof we have signed our names to this specification in the presence of two subscribing witnesses.

WILLIAM R. STONE.
ALBERT W. PRATT.
